CLAIM

The ornamental design for a bedside table, as shown and described.

DESCRIPTION

FIG. 1 is a first perspective view of a bedside table showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the portion taken at line-9 in FIG. 1.

The broken lines shown in the drawings depict portions of the bedside table that form no part of the claimed design. The alternating long and short broken lines indicate the enlarged portion of the claimed design.
